UNITED STATES PATENT OFFICE

103,775

DESIGN FOR A GAS STOVE

Alexander R. Grant, Chicago, Ill., assignor to The Moore Corporation, Joliet, Ill., a corporation of Delaware

Application January 31, 1936, Serial No. 60,930

Term of patent 14 years

To all whom it may concern:

Be it known that I, Alexander R. Grant, a citizen of the United States, residing at Chicago, county of Cook, and State of Illinois, have invented a new, original, and ornamental design for a Gas Stove, of which the following is a specification, reference being had to the accompanying drawing, forming a part thereof:

On the drawing,

The figure is a perspective view of the gas stove showing my new design.

The side of the gas stove not shown in the drawing is like the side shown.

I claim:

The ornamental design for a gas stove as shown and described.

ALEXANDER R. GRANT.
